BRAKE SHOE MOUNTING CONSTRUCTION

Steve Schnell, Kirkwood, Mo., assignor to Wagner Electric Corporation, St. Louis, Mo., a corporation of Delaware

Application June 27, 1941, Serial No. 399,971

10 Claims. (Cl. 188—78)

My invention relates to brakes and more particularly to a brake shoe mounting construction whereby the shoe may be mounted on a support, said construction being an improvement over that shown in my Patent No. 2,205,439 issued June 25, 1940.

One of the objects of my invention is to provide an improved mounting construction for a brake shoe permitting said shoe to be mounted on a support for pivotal movement about a fixed axis and for sliding movement toward the drum.

Another object of my invention is to provide an improved mounting construction for the end of a T-section brake shoe which will permit the shoe end to have a greater effective anchoring area than that which would be permitted by the normal depth of the end of the web of the shoe when said shoe is made from rough T-section stock.

Yet another object of my invention is to provide an improved mounting construction for a shoe end which will permit the pivotal axis of the anchor to be placed a greater distance from the drum than would be permitted by the normal depth of the web of the stock from which the shoe is made and at the same time not in any way weaken the shoe adjacent the anchor.

Still another object of my invention is to provide an improved anchoring construction of the type in which a plane surface on the shoe is adapted to abut a plane surface on a member pivoted to the support to thus permit the shoe to slide toward the drum in a predetermined plane yet have free pivotal movement about a fixed axis.

Other objects of my invention will become apparent from the following description taken in connection with the accompanying drawing in which Figure 1 is a side view showing my improved brake shoe mounting construction; Figure 2 is an end view of the mounting construction; Figure 3 is a sectional view taken on the line 3—3 of Figure 2; Figure 4 is a sectional view taken on the line 4—4 of Figure 1; Figure 5 is a view of the end of the brake shoe showing how the web is formed prior to the web being shaped to its final construction; and Figure 6 is a view of the end of the shoe as formed before the U-shaped bracket is welded thereto.

The brake shoe 1 is of T-shaped cross-section made from a piece of rough T-section stock. By means of the T-section there is provided a web 2 and a lining carrying flange 3 to which is secured the lining 4 for cooperation with the drum 5.

As shown in Figure 5, the end of the T-section

5 stock 6 from which the shoe is made, has its web portion 2 provided with a cut-out 7, thereby forming legs 8 and 9. The leg 8 has an end surface 10 and leg 9 has an end surface 11, said surfaces being at an angle to each other. After the T-section stock is formed, as shown in Figure 5, leg 8 is deformed with respect to the web portion by being bent away from leg 9 and to the position shown in Figure 6, this position being such that the surface 10 will be aligned with surface 11 on leg 9. Thus it is seen that by this construction that the effective (overall) depth of the web at its end is considerably increased.

10 The end of shoe 1 has secured thereto by welding, a U-shaped bracket 12 provided with legs 13 and 14 and a base portion 15, said legs receiving legs 8 and 9 of the web portion of the shoe. With the bracket secured to the end of the shoe in the manner shown in Figure 1, there is provided a slot 16 of rectangular cross-section.

15 The backing plate 17, which forms the support for the brake shoe and also closes the open side of the drum, carries an anchor pin 18 and pivotally mounted on this pin is a block 19 for positioning in the slot 16 formed by the U-shaped bracket on the end of the shoe. The thickness of the block is less than the width of the slot in order to give some clearance. The forward surface of this block is provided with a groove 20

20 provided with a curved surface for receiving the ends of legs 8 and 9 which are formed with co-operating curved surfaces (see Figure 4). In order that the shoe may have relative movement with respect to the anchor pin, legs 13 and 14 25 of the bracket are provided with oversize elongated openings 21 and 22, respectively. It is also noted that because of the oversize openings 21 and 22, the clearance between the block and U-shaped member, and the cooperating curved surfaces of the end of the legs of the web and the groove 20, the shoe is permitted to have some free lateral swinging movement to adjust itself to the drum. The cooperating curved surfaces, however, always insure that the surfaces in abutting relation will remain the same regardless of this shoe movement as the movement is about an axis which coincides with the center of the curved surfaces. The rear surface 23 of the block is adapted to engage with a portion 24 formed

30 on the lower part of the base 15 of the bracket, thus giving a supporting surface for the block at this point. The balance of the portion of the base of said bracket is spaced away from the block to provide a space 25 in which is positioned a leaf-spring 26. This spring holds the ends of the

legs of the web in frictional engagement with the block. The spring is held in position by a turned-over portion 27 on the base portion of the bracket. A washer 28 on the anchor pin 14 holds the shoe in operative position.

From the above description of my improved brake shoe mounting construction it is seen that the heel end of the shoe is free to pivot about the fixed anchor pin 18 in order to engage the shoe with the drum and disengage it therefrom. Also, the heel end of the shoe, when the shoe is engaged with the drum, can have sliding movement toward the drum and in a plane corresponding to that in which the ends of the legs of the web lie. This sliding movement permits the heel end of the shoe to automatically adjust itself so as to compensate for wear of the lining. The adjustment is maintained by the action of the leaf-spring 26 which holds the ends of legs 9 and 10 of the web in frictional engagement with the block but does not interfere with free pivoting of the shoe. The spring does not prevent adjustment from taking place, due to the superior force caused by drum rotation and acting to move the heel end of the shoe into engagement with the drum when the shoe is caused to engage therewith by the usual actuating means at the toe end of the shoe.

By forming the end of the web in the manner shown, the effective bearing surface between the shoe and the block is considerably increased over that which would be available if the depth of the end of the web, as determined by the rough T-section stock, were used. Also, by increasing the effective bearing surface, the anchor pin for the shoe can be placed farther away from the drum, thereby increasing the self-energizing action of the shoe when engaged with the drum. The construction results in a saving of material as it is not necessary to use a T-section stock which has a web depth as great as the depth of the spread-apart legs. It is old to turn up the entire end of the web to obtain a high anchor, but such construction weakens the shoe at the heel end. With my construction only a part of the web is turned up and the remaining part (leg 9) remains as originally formed and connected to the flange, thus retaining its maximum strength. The construction also permits the use of a long block which has a supporting surface 24 at its rear side opposite the end of leg 9 of the web. Such supporting surface prevents the turning of the block on the pivot and thereby diminishes or eliminates the "digging" of the upper part (leg 8) of the web into the block. The surface in contact with the block and the end of the web is additionally increased by the curved bottom groove on the block for receiving the ends of the web also provided with curved surfaces, thus giving extra support for the shoe end. Also, lateral movement of the shoe does not decrease the area of the abutting surfaces.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In braking apparatus, a drum, a support, a T-section brake shoe for cooperation with the drum and having a portion of the end of its web deformed inwardly away from the remaining por-

tion, a member secured to the end of the web, an anchor pin carried by the support, an elongated block pivoted adjacent one end on the anchor pin, the axis of said anchor pin being opposite the deformed end of the web and the two end portions of the web engaging the block in a single plane for permitting the shoe to have sliding movement relatively to the block and toward the drum when the shoe is engaged with the drum, and means on the member for cooperating with the rear side of the block at a point between the anchor pin and the drum for preventing said block from having relative rotary movement with respect to the shoe.

2. In braking apparatus, a drum, a support, a T-section brake shoe for cooperation with the drum and having a portion of the end of its web deformed inwardly from the remaining portion, a U-shaped member secured to the end of the web and forming a slot, an anchor pin carried by the support, a block pivoted on the anchor pin and positioned in the slot so as to be engaged by the end of the web, the axis of said anchor pin being opposite the deformed end of the web and the cooperating surfaces of the block and web being such as to permit the end of the shoe to have sliding movement toward the drum relatively to the block and in a selected plane when the shoe is engaged with the drum, and the rear portion of said U-shaped member being so formed as to engage the rear surface of the block and prevent it from having relative rotation with respect to the shoe.

3. In braking apparatus, a drum, a support, an anchor pin carried by the support, a T-section brake shoe, a U-shaped member secured to the end of the web of the shoe and forming therewith a slot, a block pivoted on the anchor pin and positioned in the slot for abutting engagement by the end of the web of the shoe, said U-shaped member being constructed to permit the shoe to have sliding movement relatively to the block and toward the drum during braking action, and a spring interposed between the base of the U-shaped member and the block for maintaining said block and the end of the web in frictional engagement, said U-shaped member being so formed as to engage the block at a point outwardly of the pivotal axis thereof and on the side opposite the shoe web to positively prevent turning of the block on the anchor pin relatively to the shoe.

4. In braking apparatus, a drum, a support, an anchor pin carried by the support, a T-section brake shoe, a member secured to the shoe and forming with the end of the web a slot of greater width than the web, a block pivoted on the anchor pin and positioned in the slot, the forward edge of said block being of greater width than the web and provided with a straight groove in which is received the end of said web for sliding movement toward the drum during braking action, and a spring cooperating with the member and the rear edge of the block for maintaining frictional engagement between the end of the web and the grooved surface of the block.

5. In braking apparatus, a drum, a support, an anchor pin carried by the support, a T-section brake shoe having a portion of the end of its web deformed away from the remaining portion to increase its effective overall depth at said end, a U-shaped member secured to the end of the web and forming therewith an elongated slot, an elongated block pivoted adjacent one end on the anchor pin and positioned in the slot, said block

being engaged by the ends of the two portions of the web and said member being constructed to permit the end of the shoe to have relative movement with respect to the block and toward the drum in a selected plane, a spring interposed between the base portion of the U-shaped member and the block and maintaining the ends of the two portions of the web in frictional engagement with the block, and means on the U-shaped member for cooperating with the block at a point spaced from its pivotal axis for preventing said block from having relative pivotal movement with respect to the shoe.

6. In braking apparatus, a drum, a support, an anchor pin carried by the support, a T-section brake shoe having a portion of the end of its web deformed away from the remaining portion to increase its effective overall depth at said end, a U-shaped member secured to the end of the web and forming therewith an elongated slot, an elongated block pivoted adjacent one end on the anchor pin and positioned in the slot, said block being provided with a grooved edge having a straight bottom engaged by the ends of the two portions of the web and said member being constructed to permit the end of the shoe to have relative movement with respect to the block and toward the drum in a selected plane, a leaf-spring interposed between the base portion of the U-shaped member and the rear edge of the block and maintaining the ends of the two portions of the web in frictional engagement with the groove of the block, and means on the U-shaped member for cooperating with the block at a point spaced from its pivotal axis for preventing said block from having relative pivotal movement with respect to the shoe.

7. In braking apparatus, a drum, a support, an anchor pin carried by the support, a T-section brake shoe having a straight end edge, a block pivoted on the anchor pin and provided in the edge surface thereof adjacent the shoe with a straight groove for receiving the end of the shoe web and permitting the shoe to have sliding movement in a selected plane toward the drum during braking action, said groove having its bottom surface curved and the end surface of the web being provided with a cooperating like surface to thus permit the shoe to have a limited lateral turning movement with respect to the block and without substantial decrease of the areas of the surfaces in contact, and a spring for maintaining frictional engagement between the contacting surfaces of the web and block.

8. In braking apparatus, a drum, a support, an anchor pin carried by the support, a T-section brake shoe having a straight end edge, a U-shaped member secured to the end of the shoe and forming with the end of the web a slot of

greater width than the web, a block pivoted on the anchor pin and positioned in the slot, said block also being of greater width than the web and provided on its forward edge adjacent the shoe with a straight groove for receiving the end of the shoe web and permitting said shoe to have sliding movement in a selected plane toward the drum during braking action, said groove having its bottom surface curved and the end surface of the web being provided with a cooperating like surface to thus permit the shoe to have a limited lateral turning movement with respect to the block and without substantial decrease of the areas of the surfaces in contact, and a leaf-spring cooperating with the member and the rear edge of the block for maintaining frictional engagement between the contacting curved surfaces.

9. In braking apparatus, a drum, a support, a T-section brake shoe for cooperation with the drum and being made from T-section stock in which the leg thereof forms the web of the finished shoe and is of substantially uniform depth, said stock having a portion of one end of its leg deformed away from the remaining portion thereby causing one end of the shoe web to have an overall depth greater than that of the leg of the stock, a member secured to both parts of the end of the web and forming a slot, an anchor pin carried by the support, and a block pivoted on the anchor pin and positioned in the slot so as to be engaged by both the end of the deformed part of the web and the end of the remaining portion, the axis of said anchor pin being opposite the deformed end of the web and the cooperating surfaces of the block and web being such as to permit the end of the shoe to have sliding movement toward the drum relatively to the block and in a selected plane when the shoe is engaged with the drum.

10. In braking apparatus, a drum, a support, a T-section brake shoe for cooperation with the drum and being made from T-section stock in which the leg thereof forms the web of the finished shoe and is of substantially uniform depth, said stock having a portion of one end of its leg deformed away from the remaining portion thereby causing one end of the shoe web to have an overall width greater than that of the leg of the stock, a member secured to both parts of the end of the web, an anchor pin carried by the support, and means for pivotally mounting said member on the anchor pin, the axis of said pin being positioned opposite the end of the deformed portion and spaced inwardly from the brake drum a distance at least as great as the distance from the drum to the inner edge of the web which is not deformed.

STEVE SCHNELL.
